UNITED STATES PATENT OFFICE.

KIRK H. WHITE, OF OSWEGO, NEW YORK, ASSIGNOR OF ONE-HALF TO MARSHALL S. ELY, OF NEW YORK, N. Y.

UNION SUIT.

1,093,018.

Specification of Letters Patent. Patented Apr. 14, 1914.

Application filed May 8, 1912. Serial No. 694,891.

To all whom it may concern:

Be it known that I, KIRK H. WHITE, a citizen of the United States, residing at Oswego, county of Oswego, and State of New York, have invented certain new and useful Improvements in Union Suits, fully described and represented in the following specification and the accompanying drawings, forming a part of the same.

10 This invention relates to that class of underwear known as union suits, and the invention is especially intended for knitted underwear of this class, although applicable also to union suits made wholly or partially 15 of other material.

The especial object of the invention is to provide an improved union suit of that class in which there is a permanent closure in front of the crotch between the front opening and posterior opening of the garment, and the posterior opening is closed and opened by a side flap, and particularly to provide a garment having a free opening and sure closing of the posterior opening 25 and securing comfort and proper fit, while at the same time simple and cheap of manufacture.

In the accompanying drawings forming a part of this specification, a union suit embodying the features of the invention in its preferred form is shown, and this construction will now be described, and the features forming the invention specifically pointed out in the claim.

30 35 In the drawings: Figure 1 is a perspective front view of a union suit on a wearer in a standing position; Fig. 2 is a rear elevation of the suit; Fig. 3 is a plan view looking at the crotch laid out flat, and Fig. 40 4 is a plan view of one of the two inserts used for closing the posterior opening.

Referring to the drawings, A is the main body of the union suit having the front opening 1 extending down to a point in front of or above the crotch, and shown as buttoned, as usual, and having its posterior opening extending from the end or near the end of the front opening to a point in the back such as to give the desired freedom of 45 opening and closing the posterior opening by the inner and outer seat flaps a, b, the outer flap a being shown as secured by the button 3. The inner and outer overlapping flaps a, b are formed by separate inserts, 50 preferably of the same form and as shown

in Fig. 4, which inserts extend from the center of the back down into the leg, to the inner leg seams 4, and are secured throughout their outer edges 5 and bottom edges 6 by stitching, while their inner edges 7 are free, so as to overlap and close the crotch in the normal position of the suit, while permitting the crotch to be opened up to the seamed edges 6 in front of and above the crotch.

60 It will be seen from the drawings that the lower portions of the inserts a, b, in making the suit, are carried around through the crotch to the front of the garment, and the hook-shaped portions 8 brought upward 65 out of their natural position for stitching together across the front of the suit on the lines 6, which provides a looseness or fullness of the overlapping inserts through the crotch, thus giving ample room for the person of the wearer and preventing all binding 70 in the crotch. These hook-shaped portions extending through the crotch and secured to the body across the garment in front of the crotch on their outside edges, not only prevent binding, but enable the required crotch 75 opening to be secured without such enlargement of the garment seat and crotch a would be required if the inserts were made with straight sides 6, 7, and the triangular 80 portions formed thereby carried through the crotch and the straight side 6 secured across the garment, and they also reduce the amount of cloth overlapping in the crotch, 85 so as to make a less bungling and more comfortable garment, and secure a better closing of the crotch, these hook-shaped portions tending to draw the overlapping inserts together and secure a better fitting garment.

90 The suit is shown as having its shirt and drawers portions connected by an elastic band B, formed of knit material, with the wales preferably running transversely to or around the garment for vertical elasticity, the lower edge of the band B being inclined 95 upward from the opposite sides on the back of the garment, so that the central portion of the band is higher up in the back than the side portions. This elastic band is preferably used in connection with the posterior 100 opening and crotch construction, but the invention may be used without this elastic band feature.

105 What is claimed is:

110 A union suit having a posterior opening

extending through the crotch and closed by overlapping side flaps formed by inserts *a*, *b* extending from the back down the legs and secured to the body of the suit on their outer edges and having hook-shaped portions 8 on their inner edges extending through the crotch and secured to the body across the garment in front of the crotch on their outside edges, said inserts having their inner

edges free for opening and closing the posterior opening.

In testimony whereof, I have hereunto set my hand, in the presence of two subscribing witnesses.

KIRK H. WHITE.
